RESOLING STITCHING MACHINE

John Ferrara, Rochester, N. Y.

Application March 6, 1929. Serial No. 344,699

8 Claims. (Cl. 112—45)

The present invention relates to resoling stitching machines of the type in which the shoe to be operated on is held on a work support by a presser foot and operated on by an awl and a stitching mechanism and fed forward as the work progresses. An object of this invention is to provide a cutter and means associated therewith which will operate on the sole in advance of the stitching mechanism to cut and turn back a lip to permit the stitching mechanism to operate through that portion of the sole below the lip and the welt, novel means being provided for mounting the cutting knife. Another object of this invention is to mount the cutting knife on the support or carrier for the awl to perform the cutting operation as the awl advances over the work. Still another object of the invention is to provide the presser foot with a guideway for a lip forming cutter movable relatively thereto.

To these and other ends, the invention consists of certain parts and combinations of parts, all of which will be hereinafter described: the novel features being pointed out in the appended claims.

In the drawings:

Fig. 1 is a front elevation of a stitching machine illustrating one application of the invention;

Fig. 2 is a similar view showing the parts in other positions;

Fig. 3 is an enlarged plan view of the same;

Fig. 4 is a similar view, showing the parts in another position;

Figs. 5 and 6 are detailed views of the knife and parts associated therewith detached from the machine;

Fig. 7 is an enlarged side elevation;

Fig. 8 is a similar view showing the parts in another position;

Fig. 9 is a section on the line B—B, Fig. 4; and

Fig. 10 is a section through the knife and presser foot.

In resoling shoes with a sewing or stitching machine it is customary to cut a groove in the surface of the outer sole in which the stitches of the machine are formed to secure the outer sole to the welt of the shoe, this groove being formed adjacent the edges of the sole produces an unsightly appearance in the finished work.

According to the present invention the cutting knife is arranged to make an inclined incision adjacent the edge of the sole to form a lip, means being provided for raising this lip during the stitching operation. After the stitching operation, the lip is returned to normal position and completely conceals the stitching.

Any suitable stitching machine may be used. A common and well known form comprises a work support 1 with which the welt of the shoe is engaged after the outer sole is temporarily positioned on the shoe. The shoe is held on the support and clamped thereon by a presser foot 2 detachably mounted on an oscillatory arm 3. While clamped on the work support by the presser foot a curved swinging awl 4 passes through the welt and the sole, the awl being mounted on a support 15 for reciprocatory movement transversely of its plane of operation, so that the awl serves to feed the work over the work support which is provided with a slot to permit the transverse movement of the awl. The awl makes a transverse movement in the direction to feed the work while extending through the sole and the welt, and an idle return movement after it has been withdrawn from the work to make a succession of perforations through which the stitching is passed. A curved needle 5 passes through the openings in the sole and welt made by the awl and cooperates with a looper, not shown but common in the art, to form the stitch. Detailed description of these parts is deemed unnecessary as they are old and well-known in the art.

In the present instance, the usual presser foot is removed and replaced with a combined presser foot and work gauge 6 having a part 85 extending laterally to a point in rear of the stitching needle where it is provided with an outwardly and upwardly inclined deflector 7. Mounted by means of the arm 8 on the part 15 which also carries the awl, is a cutting knife 9 having a reciprocatory movement with the awl, but which is mounted to operate on the work in advance of the awl. The combined presser foot and gauge 6 is formed of two parts secured to each other by any suitable means, as by screws as shown, and a slot or guideway for the cutting knife is provided in which the knife is mounted and moves. The knife or cutter projects forwardly from the slot and is inclined slightly downwardly but has its cutting edge 100 substantially in the plane of the sole.

It will be noted that the work operated on is held between the work support 1 and the presser foot 6 and against a gauge 6^a combined with the presser foot and adapted to limit the movement of the work toward the knife and guide it on its support as the work progresses. The knife forms a slit in the outer sole adjacent its edge in advance of the action of the awl and stitching devices and the deflector 7 en-

gages the lip formed by the cutter in rear of said devices and raises it to a substantially vertical position during the stitching operation. It will also be noted that the awl moves the work 5 to advance it from stitch to stitch and that the knife moves with it and the work, the cutting being performed on the return stroke when the awl is free from the work, thus avoiding undue strains on the awl causing it to bend or 10 break as might be the case if the awl moved the work against the knife to perform the cutting operation. The invention disclosed herein is in the nature of an attachment for a resoling stitching machine. The usual presser foot is detached and replaced by the combined presser 15 foot and work gauge. The presser foot and work gauge extend across the stitching devices where it is provided with the deflector and a guideway for the lip cutter which is arranged 20 between the deflector and the presser foot, the lip cutter being adapted to be mounted on the awl support 15 and arranged in the guideway to move transversely with the awl. The awl support is mounted in a guideway 16 and is reciprocated by the bell crank 17 one arm of which is engaged by the cam 18. The presser foot arm or support 19 has a handle 20 by means of 25 which it may be lifted from the work about the pivot 21.

30 What I claim as my invention and desire to secure by Letters Patent is:

1. In a resoling machine, the combination of a work support, a presser foot cooperating therewith to hold a work piece and having a gage for engagement with the edge of the work piece, an awl adapted to operate on and movable to feed the work piece on its support, a stitching mechanism operating through the openings formed by the awl, a lip forming cutter movable with the awl and adapted to engage the work to form a lip, 35 said cutter having its cutting plane substantially parallel with the plane of the sole to be cut and means for supporting said cutter so that its cutting takes place from the gage inward.

40 2. In a resoling machine, the combination of a work support, a presser foot cooperating therewith to hold a work piece, an awl adapted to operate on and movable to feed the work piece on its support, a stitching mechanism operating through the openings formed by the awl, a lip forming cutter movable with the awl and having its cutting edge substantially parallel with the plane of the work, and a deflector for engaging the lip formed by the cutter to hold the lip elevated while the awl and stitching devices operate 45 on the work said deflector being arranged in rear of the awl.

50 3. In a resoling machine, the combination of a work support, a presser foot cooperating therewith to hold a work piece, an awl adapted to operate on and movable to feed the work piece on its support, a stitching mechanism operating through the openings formed by the awl, a lip forming cutter movable relatively to the presser 55 foot and engaging the work to form a lip, and having its cutting edge substantially parallel with the plane of the work and a deflector for engaging the lip formed by the cutter to hold the lip

elevated while the awl and stitching devices operate on the work said deflector being arranged in rear of the awl.

4. In a resoling machine, the combination of a work support, a presser foot cooperating therewith to hold a work piece, a guideway in the presser foot, a knife movable in the guideway adapted to cut a lip in the work piece, a deflector rigid with the presser foot adapted to engage the lip formed by the knife to hold the lip elevated, and an awl and stitching devices operating on the work between the knife and the deflector while the lip is elevated. 80

5. In a shoe resoling machine, the combination of a welt engaging work rest lying entirely to one side of an upper of a shoe, the welt of which is engaged by the work rest, a presser foot carrying lever mounted to move toward and from the work rest, a frame carried by said lever, and a presser foot carried by said frame to engage the outer face of the sole directly above the work rest, of a gage carried by the frame to engage the edge of the sole at a point directly opposite the point engaged by the presser foot, a guide on the frame, a knife movable on said guide to cut a lip in the work piece, a deflector carried by the frame and adapted to engage the lip formed by the knife to hold the lip elevated, and an awl operating on the work while the lip is elevated. 85

6. In a shoe resoling machine, the combination of a welt engaging work rest lying entirely to one side of an upper of a shoe, the welt of which is engaged by the work rest, a presser foot carrying lever mounted to move toward and from the work rest, a frame carried by said lever, and a presser foot carried by said frame to engage the outer face of the sole directly above the work rest, of a lip deflector rigid with the frame, a work gage on the frame, a guideway on the frame, and a lip forming cutter movable on the guideway 90
